TRIMMER MECHANISM FOR SEWING MACHINES

Frank Parry, Bridgeport, Conn., assignor to The Singer Manufacturing Company, Elizabeth, N. J., a corporation of New Jersey

Application May 7, 1940, Serial No. 333,707

17 Claims. (Cl. 112—125)

This invention relates to trimmer mechanisms for sewing machines and has for its primary object to provide improved means for controlling the effective action of trimmer-actuating mechanisms adapted to be thrown into and out of operation at will during the operation of the machine. More specifically, an object of the invention is to provide a trimmer-knife actuating mechanism, which may be at will rendered ineffective without disconnecting the component elements of said actuating mechanism, with manually operable means for disabling and for rendering effective the trimmer-knife actuating train of connections.

The invention has for a further object to provide a trimmer mechanism of sturdy construction particularly adapted to trim heavy work, in combination with manually controlled means for positively shifting the trimmer-knife from inoperative to operative positions thereof when the disabled trimmer-actuating mechanism is rendered effective.

Other and more specific objects of the invention will be apparent from the following description and claims.

The present invention is in the nature of an improvement in the toggle-link trimmer-actuating mechanism forming the subject of the U. S. Patent to B. P. Pinkvoss, No. 2,202,599, May 28, 1940, and consists in the trimmer-knife actuating and controlling mechanism hereinafter described in connection with the accompanying drawings which illustrate a preferred embodiment of the invention and in which:

Fig. 1 is a view in front side elevation and partly in vertical section of a portion of a sewing machine containing the improved trimmer mechanism. Fig. 2 represents a front end elevation of the sewing machine shown partly broken away. Fig. 3 represents a top plan view of the trimmer mechanism, a part of the machine frame and the knife-bar being illustrated in horizontal section. Fig. 4 represents a cross-sectional view of the bracket-arm of the machine, substantially on the line 4—4 of Fig. 1, and showing the trimmer rock-shaft actuating connections in an operative position thereof. Fig. 5 shows in side elevation, and partly in section, the trimmer-actuating connections illustrated in Fig. 4, but in the inoperative position of said connections. Fig. 6 represents a detail cross-section of the toggle-links and spring-latch employed for actuating the trimmer rock-shaft. Fig. 7 represents in perspective, and partly in section, the cooperating movable and stationary trimmer-knives and the supporting means therefor. Fig. 8 represents a bottom plan

view, partly in horizontal section, of the ledger-blade supporting bracket. Fig. 9 represents a horizontal section of the knife-holder guide-block and guideway in the plane of the axis of pivotal connection of the knife-bar actuating link with the guide-block.

The sewing machine illustrated in the drawings has a frame including the usual work-supporting bed-plate 1 and overhanging bracket-arm 2 terminating in a head 3. Rotatably journaled in suitable bearings provided in the bracket-arm 2 is a horizontally disposed main actuating shaft 4 carrying at one end a crank-disk 5. The crank-disk 5 is provided with the usual crank-pin 6 connected by a link 7 with a vertically disposed needle-bar 8 journaled for endwise reciprocation in suitable bearings in the bracket-arm head 3. At its lower end, the needle-bar 8 carries an eye-pointed needle 9.

Complemental to the needle 9 in the formation of lock-stitches is a horizontal-axis rotary loop-taker 10 disposed below the bed-plate 1 and adapted to cast needle-thread loops about a thread-carrier 11 journaled in and suitably restrained against rotation with said loop-taker. The loop-taker 10 may be actuated in any suitable manner and it is to be understood that any other preferred form of stitch-forming mechanism may be substituted for that contained in the present sewing machine.

The work may be advanced past the stitch-forming mechanism by any usual or suitable feeding mechanism, the present machine having for that purpose a feed-dog 12 of the drop-feed type. The feed-dog 12 is opposed by a presser-foot 13 secured to the lower end of a spring-depressed presser-bar 14 which is endwise movable vertically in suitable bearings provided in the bracket-arm head 3.

The present invention relates more particularly to the trimmer mechanism embodied in the sewing machine referred to and including a vertically movable trimmer-knife 15. The trimmer-knife 15 is angular in cross-section, having a pilot-wing 16 depending vertically from a lateral cutter-wing 17 substantially normal to the pilot-wing 16, and an attaching rib 18 rising vertically from the cutter-wing 17. The trimmer-knife 15 is lengthwise inclined to the work-support 1, the effective end of the pilot-wing 16 being vertically disposed and the adjacent end portion of the cutter-wing 17 providing a cutting-edge 17'.

The trimmer-knife 15 is carried by a vertically disposed knife-holder plate 19 which is suitably recessed in a side face thereof to provide a seat

for one side and the upper edge of the attaching-rib 18 of the knife. The opposite face of the attaching-rib 18 of the knife is engaged by a clamp-plate 20 secured to the knife-holder plate 19 by a screw 21, said clamp-plate 20 being recessed to receive the cutter-wing 17 of the knife, whereby the trimmer-knife 15 is rigidly but endwise adjustably secured to the knife-holder plate 19.

The knife-holder plate 19 is carried by the lower end of a vertically disposed knife-bar 22 journaled for endwise movement in a vertically apertured bushing 23. The bushing 23 is secured by screws 24 in a frame-boss 25 provided at the front side of the bracket-arm head 3.

The bushing 23 extends below the frame-boss 25, and clamped to the projecting portion of said bushing 23, by a screw 26, is the split-hub of a guide-frame holder 27. Secured by a screw 27 to the holder 27 is a vertically depending guide-frame 28, which is channeled to provide a lengthwise vertically extending and forwardly open guideway 29, in which is slidably disposed the split end portion 30 of a guide-block 31 extending rearwardly from and preferably integral with the knife-holder plate 19. A tapered screw 32 threaded into the split-end portion 30 of the guide-block provides for adjustably spreading said portion 30, thereby to take up wear, the screw 32 being accessible through a suitable aperture 33 provided in the rear wall of the guide-way 29.

Connected to the guide-block 31 by a pivot-bolt 34 is the lower end of a link 35 disposed adjacent to the frame-boss 25, the upper end of said link being connected by a pivot-bolt 36 to a crank-arm 37 extending forwardly from and having a split hub clamped upon one end of a knife-actuating rock-shaft 38. The rock-shaft 38 is journaled horizontally in bushings 39 and 40 secured, respectively, in spaced bearing-lugs 41 and 42 depending from a supporting bracket 43, said bracket 43 being secured by screws 44 to the flattened under side of the bracket-arm 2.

The bushing 40 and the rock-shaft 38 journaled therein extend through an aperture 45 in a depending portion of the wall of the bracket-arm 2 adjacent the bearing-lug 42 of the supporting bracket 43, and the front wall of the bracket-arm 2 is provided with an opening 46 closed by an inwardly flanged cover-plate 47 detachably secured to the bracket-arm 2 by screws 48.

Clamped by a screw 49 upon the end of the rock-shaft 38 within the bracket-arm 2 is the split hub of a forwardly extending crank-arm 50. The free end of the crank-arm 50 is connected by a pivot-bolt 51 to one end of a lower toggle-link 52. At its opposite end, the toggle-link 52 has a fork 53 receiving the lower end of a complementary or upper toggle-link 54 connected to the link 52 by a pivot-pin 55 disposed substantially parallel to the pivot-bolt 51. The upper toggle-link 54 has a split strap 56 embracing an actuating element in the form of an eccentric 57 carried by the actuating shaft 4, and the lower end of said link 54 has an offset extension 58 adapted to engage the rearward side of the toggle-link 52 in the toggle-straightened or operative position of said links. A spring-latch 59 (Fig. 6) is secured by screws 60 to the toggle-link 52 in position to engage the extension 58 of the link 54, thereby to hold the links 52, 54 releasably in the toggle-straightened position thereof.

It will be understood from the foregoing description that the pivotal axes 51 and 55 of the

toggle links 52, 54, are disposed in parallelism with the axis of rotation of the bracket-arm shaft 4. It will be further understood that in the alined or toggle-straightened position of the links 52, 54, illustrated in Fig. 4 of the drawings and releasably maintained by the spring-latch 59, the two links together function as a pitman to transmit oscillatory movements to the rock-shaft 38, thereby vertically reciprocating the knife-bar 22 and imparting work-severing movements to the trimmer-knife 15.

Disposed substantially parallel to the rock-shaft 38, at the rear side of the bracket-arm 2 and journaled in suitable bearings, of which one is in the present case provided by the lug 42, is a controller rock-shaft 60. Suitably secured to said controller rock-shaft 60 is a crank-arm 61 extending forwardly through an opening 62 provided in the rear wall of the bracket-arm 2, said crank-arm having its forward free end disposed within the bracket-arm 2 and connected as by a chain 63 to a suitable treadle or knee-shift device (not shown). A spring 64 is anchored to a post 65 at the rear side of the bracket-arm 2 and bears against the crank-arm 61 in a direction to bias said crank-arm upwardly.

Secured to the controller rock-shaft 60, by a clamp-screw 66, is the split-hub of a toggle-straightening arm 67 extending forwardly from the rock-shaft through an opening 68 in the rear wall of the bracket-arm 2. The forward or free end of the toggle-straightening arm 67 is adapted to engage the rear face of the upper toggle-link 54 adjacent to the knuckle of the links 52, 54, in the toggle-broken position of said links illustrated in Fig. 5 of the drawings. By depressing the treadle-actuated arm 61 of the rock-shaft 60, against the action of the spring 64, the rock-shaft 60 is actuated to cause the arm 67 to engage the toggle-link 54 and thereby to bring the links 52, 54 into alined or toggle-straightened position thereof wherein the two links are releasably connected together by the spring-latch 59. The crank-arm 61, the rock-shaft 60 and the toggle-straightening arm 67 together comprise a lever affording the requisite power to straighten the toggle links, thereby forcing the trimmer-knife downwardly through work, when in cutting position upon the work-support.

Also secured to the controller rock-shaft 60, by a clamp-screw 69, is the split-hub of a knife-bar lifter arm 70. The arm 70 extends forwardly from the rock-shaft 60 through the bracket-arm opening 68 and is bent downwardly and rearwardly about the crank-arm 50 into U-shape, whereby the rearwardly extending free end portion 70' of the arm 70 underlies the crank-arm 50 of the knife-actuating rock-shaft 38.

Attached by a pivot-bolt 71 to the downwardly bent portion of the arm 70 is an angular toggle-breaking lever 72, 73, the arm 72 of said lever extending forwardly through a vertical-slot 74 formed in the bracket-arm cover-plate 47. The outer end of the lever-arm 72 is preferably horizontally flattened to provide a finger-piece 72'.

The arm 73 of the toggle-breaking lever extends upwardly from the pivot-bolt 71 and, in the operative position of the toggle-links 52, 54, the free end of the arm 73 is positioned to underlie and engage an angular latch-plate 75 suitably secured to the cover-plate 47 to extend inwardly therefrom, thereby releasably latching the knife-bar lifter-arm 70 in a position thereof wherein the portion 70' of said lifter-arm is held spaced from the crank-arm 50. In order to maintain

the lever 72, 73 releasably in the lifter-arm latching position thereof illustrated in Fig. 4 of the drawings, there is provided a spring 95 which engages the lever-arm 72 and biases said lever into a position wherein a stop-pin 75 carried by the lever-arm 73 engages a stop-pin 76 carried by the lifter-arm 70. At its upper free end, the lever-arm 73 has a rearwardly extending nose 73' adapted to engage the toggle-link 52, adjacent or substantially at the knuckle of the links 52, 54, when the toggle-breaking lever 72, 73 is manually actuated by swinging the lever-arm 72 upwardly.

The lever-nose 73' is thereby caused to bear against the toggle-link 52, thus releasing the toggle-link 54 from the latch 58 and initiating breaking of the toggle, and this may of course be effected at will during the operation of the machine, inasmuch as the lever 72, 73 is normally stationary. In the rearward or toggle-breaking movement of the lever-arm 73, the upper end of said arm clears the latch-plate 47', whereupon the spring 64 is free to turn the rock-shaft 60 in a direction to cause the rearwardly extending portion 70' of the lifter-arm 70 to engage the under side of the crank-arm 50, thereby completing breaking of the toggle-links 52, 53 and, at the same time, turning the rock-shaft 38 in a direction to raise the trimmer-knife 15 into an inoperative position thereof. The inoperative position of the trimmer-knife 15 is determined in the present machine by the engagement of the knife-holder plate 19 with the lower end of the knife-bar bushing 23. The eccentric 57 now idly actuates the toggle-links 52, 53, and the trimmer-knife 15 therefore remains stationary in its inoperative position until again thrown into operation by actuation of the controller rock-shaft 60.

While the rock-shaft 60 may be actuated by the described treadle connections therewith to straighten the toggle-links 52, 54, the straightening of said links may also be effected by bearing downwardly upon the finger-piece 72' of the lever 72, 73. The engagement of the stop-pins 75, 76 causes the lever 72, 73 to be rigid with the lifter-arm 70 when the operator bears downwardly upon the finger-piece 72' of said lever 72, 73. Consequently, the toggle-links 52, 54, may be straightened, as well as broken, by manual operation of the lever 72, 73.

The reciprocating trimmer-knife 15 coacts with a stationary ledger-blade 77 lengthwise inclined vertically and widthwise disposed substantially parallel to the line of seam formation. The ledger-blade 77 is supported by an inverted U-shaped bracket 78 providing depending end-flanges 79 and 80, said bracket having a slot 81 elongated transversely of the line of seam formation to receive bracket-securing screws 82 threaded into the under side of the bed-plate 1. The upper face of the bracket 78 has a guide-rib 83 adjustably disposed in a corresponding recess in the under side of the bed-plate 1, the described arrangement providing for adjustment of the bracket 78 crosswise of the line of seam formation.

The bracket-flange 80 is provided in its outer face with a vertically inclined channel 84 receiving the ledger-blade 77, the latter being clamped against the flange 80 by the laterally notched head 85 of a securing-pin 86. The securing-pin 86 passes through suitable guide-apertures in the bracket-flanges 79 and 80, and the end of the securing-pin opposite to the head 75

85 thereof is threaded to receive a clamping-nut 87. The arrangement described provides for convenient adjustment of the ledger-blade 77 in a vertically inclined direction, the upper edge 77' of said ledger-blade being preferably slightly inclined upwardly toward the rearward edge thereof. The ledger-blade 77 is positioned so that the end of the pilot-wing 16 of the reciprocating trimmer-knife 15 slidingly engages the adjacent side face of the ledger-blade 77, whereby the coacting blades are relatively properly positioned to effect work-severing coaction of the cutting-edge 17' of the knife 15 with the proximate upper edge 77' of the ledger-blade.

15 In the present machine a transverse binder 88 is disposed between the trimming zone and the needle, and it is therefore desirable to divert the trimmed-off margin of the work immediately at the trimming zone. To this end, a deflector-plate 89 is secured to the reciprocating knife-holder by the knife-clamping plate securing screw 21, the lower edge of said deflector-plate 89 descending slightly below the upper face of the bed-plate 1 during the work-severing operation and thereby crowding the trimmed-off work-margin downwardly through an opening 90 in the bed-plate 1.

30 Secured by a screw 91 to the ledger-blade bracket-flange 80 is a depending ear 92 of a chute 93 disposed in the bed-plate opening 90 and inclined downwardly in a direction away from the bracket-flange 80. The front and rearward end portions of the chute 93 are bent upwardly to provide ears or flanges 94 which serve as side guides directing the trimmed-off work-margins downwardly along and off the free edge of the chute, where said trimmed-off work-margins are free to fall through the bed-plate opening 90 without fouling the actuating mechanism of the sewing machine.

Having thus set forth the nature of the invention what I claim herein is:

1. In a trimmer mechanism for sewing machines comprising, an actuating element, a trimmer-knife carrier, and an operative train of connections for actuating said carrier from said element including a pair of toggle-links relatively movable into and out of toggle-straightened operative position, the improvement which consists in the provision of a normally stationary and manually operable toggle-breaking member disposed for engagement with said toggle-links in the toggle-straightened position of said links.

2. In a trimmer mechanism for sewing machines comprising an actuating element, a trimmer-knife carrier, and an operative train of connections for actuating said carrier from said element including a pair of toggle-links relatively movable into and out of toggle-straightened operative position, the improvement which consists in the provision of a normally stationary and manually operable toggle-straightening member disposed for engagement with said toggle-links in the toggle-broken position of said links.

3. In a trimmer mechanism for sewing machines comprising, an actuating element, a trimmer-knife carrier, and an operative train of connections for actuating said carrier from said element including a pair of toggle-links relatively movable into and out of toggle-straightened operative position, the improvement which consists in the provision of normally stationary means actuatable for straightening and for buckling said toggle-links.

4. In a trimmer mechanism for sewing machines comprising an actuating element, a trimmer-knife carrier, and an operative train of connections for actuating said carrier from said element including a pair of toggle-jointed links, the improvement which consists in the provision of manually operable means separate from said links for at will relatively moving said links into and out of toggle-straightened operative position thereof.

5. In a trimmer mechanism for sewing machines comprising an actuating element, a trimmer-knife carrier, and an operative train of connections for actuating said carrier from said element including a pair of toggle-jointed links, the improvement which consists in the provision of manually operable lever means engageable in opposite directions with said toggle-links for at will relatively moving said links into and out of toggle-straightened operative position thereof.

6. In a trimmer mechanism for sewing machines comprising, an actuating element, a trimmer-knife carrier, an operative train of connections for actuating said carrier from said element including a pair of pivotally jointed toggle-links, and releasable means for latching said toggle-links in toggle-straightened operative position, the improvement which consists in the provision of a lever engageable with said toggle-links in a direction transverse to the axis of pivotal connection of said links.

7. In a trimmer mechanism for sewing machines comprising, an actuating element, a trimmer-knife carrier, an operative train of connections for actuating said carrier from said element including a pair of pivotally jointed toggle-links, and releasable means for latching said toggle-links in toggle-straightened operative position, the improvement which consists in the provision of a lever engageable with said toggle-links in a direction to buckle said links and thereby to effect release of said links from said latching means, and yielding means for normally maintaining said lever in ineffective position.

8. In a trimmer mechanism for sewing machines comprising, an actuating element, a trimmer-knife carrier, an operative train of connections for actuating said carrier from said element including a pair of pivotally jointed toggle-links, and releasable means for latching said toggle-links in toggle-straightened operative position, the improvement which consists in the provision of a lever engageable with said toggle-links in a direction to initiate buckling of said links and thereby to effect release of said links from said latching means, and spring-biased means for completing buckling of said toggle-links into a position thereof ineffective to actuate said trimmer-knife carrier.

9. In a trimmer mechanism for sewing machines comprising, an actuating element, a trimmer-knife carrier, an operative train of connections for actuating said carrier from said element including a pair of pivotally jointed toggle-links, and releasable means for latching said toggle-links in toggle-straightened operative position, the improvement which consists in the provision of means for disabling said toggle-links, said means comprising a spring-biased knife-carrier lifter-arm, a pivotal support for said arm, a manually operable lever pivotally mounted upon said arm and engageable with said toggle-links in a direction to buckle said toggle-links, and means engageable by said lever for releasably maintain-

ing said arm and said lever in ineffective positions thereof.

10. In a trimmer mechanism for sewing machines comprising an actuating element, a trimmer-knife carrier, an operative train of connections for actuating said carrier from said element including a pair of pivotally jointed toggle-links, and releasable means for latching said toggle-links in toggle-straightened operative position, the improvement which consists in the provision of a manually operable controller rock-shaft, and devices carried by said rock-shaft for relatively moving said toggle-links into and out of toggle-straightened operative position.

15 11. In a trimmer mechanism for sewing machines comprising, an actuating element, a trimmer-knife carrier, an operative train of connections for actuating said carrier from said element including a pair of pivotally jointed toggle-links, and releasable means for latching said toggle-links in toggle-straightened operative position, the improvement which consists in the provision of a manually operable controller rock-shaft lengthwise disposed substantially parallel to the axis of pivotal connection of said toggle-links, an arm carried by said rock-shaft, a manually operable toggle-breaking lever pivotally mounted upon said arm and engageable with said toggle-links in a direction to buckle said links, and a toggle-straightening arm carried by said rock-shaft for engagement with said toggle-links in a toggle-broken position of said links.

30 12. A trimmer mechanism for sewing machines comprising, a rotary actuating shaft, an actuating element carried by said shaft, a trimmer-knife carrier, a knife-carrier actuating rock-shaft, connections for actuating said rock-shaft from said actuating element including a pair of pivotally-jointed toggle-links, releasable means for latching said toggle-links in toggle-straightened operative position thereof, a manually operable controller rock-shaft, manually operable toggle-breaking means carried by said controller rock-shaft for buckling said toggle-links, releasable means for maintaining said toggle-breaking means ineffective during operation of said trimmer-knife carrier, and toggle-straightening means carried by said controller rock-shaft for engagement with said toggle-links in a toggle-broken position of said links.

35 13. A trimmer mechanism for sewing machines comprising, a rotary actuating shaft, an actuating element carried by said shaft, a trimmer-knife carrier, a knife-carrier actuating rock-shaft disposed substantially parallel to said actuating shaft, a crank-arm carried by said rock-shaft, pivotally jointed toggle-links connecting said actuating element to said crank-arm, the axis of pivotal connection of said toggle-links being disposed substantially parallel to the axis of rotation of said actuating shaft, releasable means for latching said links in toggle-straightened operative position thereof, a controller rock-shaft disposed substantially parallel to said knife-carrier actuating rock-shaft, manually operable means for actuating said controller rock-shaft, a knife-carrier lifting arm extending from said controller rock-shaft and adapted to engage said crank-arm in a direction to buckle said toggle-links, a manually operable toggle-breaking lever pivotally mounted upon said lifting arm for initiating buckling of said toggle-links, releasable means for maintaining said toggle-breaking lever and lifting arm in ineffec-

tive position during operation of said trimmer-knife carrier, and a toggle-straightening arm carried by said controller rock-shaft for engagement with said toggle-links in a toggle-broken position of said links.

14. The combination in a sewing machine having a frame including a hollow bracket-arm, and a rotary actuating shaft journaled in said bracket-arm, of a trimmer mechanism comprising a trimmer-knife carrier, a rock-shaft disposed substantially parallel to said actuating shaft and connected to actuate said knife-carrier, connections disposed within said bracket-arm for actuating said rock-shaft from said rotary actuating shaft including a pair of pivotally-jointed toggle-links, releasable means for maintaining said toggle-links in toggle-straightened operative position thereof, and means manually operable at will during the operation of the machine for buckling said toggle-links.

15. The combination in a sewing machine having a frame including a hollow bracket-arm, and a rotary actuating shaft journaled in said bracket-arm, of a trimmer mechanism comprising a trimmer-knife carrier, a rock-shaft disposed substantially parallel to said actuating shaft and connected to actuate said knife-carrier, connections disposed within said bracket-arm for actuating said rock-shaft from said rotary actuating shaft including a pair of pivotally-jointed toggle-links, releasable means for maintaining said toggle-links in toggle-straightened operative position thereof, manually operable means at the front side of said bracket-arm for buckling said toggle-links, a manually

operable controller rock-shaft disposed at the rear side of said bracket-arm, and a toggle-straightening arm carried by said controller rock-shaft.

16. Trimmer mechanism for sewing machines comprising, a rotary actuating shaft, an endwise reciprocating knife-bar, a trimmer-knife carried by said knife-bar, a rock-shaft disposed substantially parallel to said rotary actuating shaft and connected to reciprocate said bar, an eccentric carried by said rotary actuating shaft, a crank-arm carried by said rock-shaft, a link having a strap embracing said eccentric, a second link pivotally connected to said first named link and pivotally connected to said crank-arm, the axes of said pivotal connections being disposed substantially parallel to the axis of rotation of said rotary actuating shaft, and means releasable at will during the operation of the machine for maintaining said links in a toggle-straightened operative position thereof.

17. In a trimmer mechanism for sewing machines, an actuating eccentric rotatable about an axis, a trimmer-knife carrier, a pitman comprising a pair of toggle-links pivotally connected together for movement relative to each other about an axis substantially parallel to the axis of rotation of said eccentric, means for releasably latching said toggle-links in toggle-straightened relation thereof, one of said toggle-links having a strap embracing said eccentric to derive endwise and sidewise movements therefrom, and operative connections with the other of said toggle-links for actuating said carrier.

35.

FRANK PARRY.
